UNITED STATES PATENT OFFICE

124,752

DESIGN FOR A SMOKING PIPE

Willard R. Richards, Buffalo, N. Y.

Application October 12, 1940, Serial No. 95,803

Term of patent 3½ years

To all whom it may concern:

Be it known that I, Willard R. Richards, a citizen of the United States, residing at Buffalo, in the county of Erie and State of New York, have invented a new, original, and ornamental Design for a Smoking Pipe, of which the following is a specification, reference being had to the accompanying drawing, forming a part thereof.

Figure 1 is a side elevation of the smoking pipe embodying my design. Figure 2 is a top plan view thereof. Figure 3 is an end view of the same.

I claim:

The ornamental design for a smoking pipe, substantially as shown.

WILLARD R. RICHARDS.
